Filed Nov. 9, 1959, Ser. No. 851,712

4 Claims. (Cl. 181—54)

This invention relates to sound attenuating or sound absorbing devices and more especially to sound attenuating apparatus, muffler or silencer for use with the exhaust gas system of an internal combustion engine of a vehicle for attenuating or absorbing sound waves entrained in a gas stream.

Mufflers or silencers have been employed with exhaust gas streams constructed with interior gas passage tubes in communication with high frequency resonating chambers for attenuating high frequency sound waves and a resonator or resonating chamber of the so-called "dead" type for attenuating low frequency sound waves principally by sound absorption. The low frequency resonator or chamber, in effect, provides a sound trap in which low frequency sound waves are substantially dissipated by absorption. In muffler constructions embodying a "dead" low frequency sound attenuating chamber, the exhaust gases do not circulate through this chamber even though it is disposed with respect to the gas stream so that low frequency waves enter and are dissipated or attenuated therein.

While sound attenuating constructions of this character have been used, they have several disadvantages. The length of the muffler is relied upon to attenuate a substantial proportion of sound waves in an exhaust gas stream, and the employment of one or more low frequency chambers disposed so that the exhaust gases do not flow through the chamber or chambers limits or decreases the effective length of the sound attenuating system thereby limiting the range of sound wave attenuation. Exhaust gases of internal combustion engines are usually very hot, with temperatures upwards of 1200° F. or more and the gas passage tubes and walls of the muffler construction in direct contact with the gases become highly heated while the "dead" resonator chamber is at much lower temperatures because of lack of circulation or movement of exhaust gases therethrough. Thus, within a muffler of this character, extreme temperature differentials exist and, upon cooling of the muffler, condensation of moisture takes place particularly in the "dead" chamber and the formation of rust and deterioration are augmented, and the useful life of such a muffler shortened where the components of the muffler construction are fabricated of ferrous metals.

The present invention embraces the provision of a muffler construction or sound attenuating means usable with a moving gas stream wherein the gases of the stream are circulated throughout all of the interior regions of the muffler construction, the muffler embodying low frequency sound attenuating chambers arranged whereby circulation of gases takes place in the low frequency sound attenuating chambers.

The invention has for an object the provision of a sound attenuating apparatus or muffler wherein the sound attenuating system includes gas passage means in conjunction with low frequency resonators or sound wave attenuating chambers disposed in adjacent relation with a connecting medium between the resonators proportioned or tuned to provide for the attenuation of sound waves of a desired range of frequencies.

Another object of the invention is the provision of a muffler or silencer construction embodying dual resonators for attenuating low frequency sound waves wherein

2

the resonators are formed by a common wall or baffle and are connected by a tuning coupling which may be proportioned or adjusted to vary the frequency range of attenuation of the resonators in conjunction with gas passage means in the muffler arranged whereby gases moving through the muffler are circulated through the resonators to establish substantially uniform temperature throughout the various regions of the muffler construction to minimize the condensation of moisture.

Another object of the invention resides in the provision of a muffler embodying gas passage means and sound attenuation means of substantial length including dual low frequency resonator chambers arranged whereby an increased range of frequencies may be attenuated without enlarging the muffler construction.

Still another object of the invention is the provision of a multi-pass muffler embodying dual low frequency sound attenuating chambers, high frequency attenuating means and gas passage means in combination with partitions arranged whereby all of the interior regions of the muffler construction are directly subjected to heat from the exhaust gas stream and the circulating exhaust gases preventing or minimizing the formation of moisture condensation within the muffler and reducing temperature differentials within the muffler.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

FIGURE 1 is a longitudinal sectional view of a muffler construction of the invention, the view being taken substantially on the line 1—1 of FIGURE 2;

FIGURE 2 is an enlarged transverse sectional view taken substantially on the line 2—2 of FIGURE 1;

FIGURE 3 is a fragmentary detail sectional view illustrating a modification of a portion of the construction shown in FIGURE 2;

FIGURE 4 is a schematic longitudinal sectional view illustrating another form of the muffler construction of oval cross section of the invention;

FIGURE 5 is a schematic longitudinal sectional view illustrating another form of muffler construction of oval cross section of the invention;

FIGURE 6 is a schematic longitudinal sectional view illustrating another form of muffler construction of oval cross section of the invention; and

FIGURE 7 is a schematic longitudinal sectional view illustrating a further form of muffler construction of oval cross section of the invention.

While the preferred arrangements or constructions of the invention illustrated in the drawings are of the type or character particularly adapted for attenuating and absorbing sound waves entrained in exhaust gas streams from internal combustion engines, it is to be understood that the principles of the invention may be utilized in other forms of sound attenuator or silencer.

Referring to the drawings in detail and initially to the construction shown in FIGURES 1 and 2, the muffler is inclusive of an elongated housing, casing or shell 10 preferably of the double wall type comprising an inner layer of sheet metal 12 and an outer layer 14 of sheet metal. The inner and outer layers 12 and 14 are preferably of independent sheets of metal but it is to be understood that the shell construction of the muffler may be a single wall or a double wall wherein a single sheet of metal is rolled upon itself with indentations or ridges

spacing the overlapping regions of the multiple wall construction.

As particularly shown in FIGURE 2, the outer layer 14 is formed with inwardly extending flutes or recesses 16 arranged longitudinally of the shell or housing and spaced circumferentially to provide inwardly extending ridges which engage the inner layer 12 to space the inner and outer layers or sheets as shown in FIGURE 2.

The meeting edge regions of the inner and outer layers are folded or bent upon themselves to form an interlock or longitudinally extending bead as at 18, the folded or bent portions of the sheets being crimped to form a fluid-tight seam or juncture extending lengthwise of the muffler construction.

It is found that a double walled arrangement for the muffler shell or housing reduces to a large extent so-called "shell" noise. As particularly shown in FIGURE 2, the cross-sectional configuration or shape of the muffler construction or shell is generally oval or ellipsoidal, but it is to be understood that the shell or casing cross-sectional configuration may be circular or other shape if desired.

The shell or casing construction is provided with end walls, heads or closures 20 and 22 of sheet metal, each of the heads or closures being formed with a peripheral flange configuration 24 of generally U-shaped cross-section providing a peripheral recess or groove which receives the mating or engaging end regions of the shell walls or layers 12 and 14 in the manner shown in FIGURE 1. It should be noted that the end regions of the layers 12 and 14 are brought into contiguous engagement and are embraced in the respective recesses provided by the flange constructions 24.

In assembly, the outermost flange portion is crimped so as to form a fluid-tight juncture between the ends of the shell layers and the end heads or walls 20 and 22.

It should be noted that the ridges or lands, provided by the recesses 16, in one of the layers engaging the other layer form individual chambers in the space between the shell layers extending lengthwise of the muffler, the longitudinally extending chambers being isolated one from another preventing circulation of air between the layers peripherally of the shell construction.

The longitudinally extending chambers 26 are isolated from the interior region defined by the inner shell wall 12 of the muffler construction, the confined zones or elongated chambers 26 forming individual air cushions which assist in reducing shell noise or vibration. The end closure or head 20 at the inlet end of the muffler is formed with a circular flange 28 defining an opening adapted to accommodate a coupling sleeve or tubular fitting 30 extending therethrough as shown in FIGURE 1.

The portion of the fitting 30 exteriorly of the end head 20 is formed with a slot 32, and is adapted to be telescoped with an exhaust pipe from an engine, and a clamping means (not shown) applied to this region of the fitting to draw the fitting into snug engagement with the exhaust pipe. The end head 22 is formed with an opening defined by a circular flange 36, the opening adapted to accommodate a coupling sleeve or tubular fitting 38 of the same type as the coupling 30.

The coupling 38 at its end region is formed or provided with a slot 40 and is adapted to be telescoped with a tail pipe for conveying gases away from the muffler, a clamp (not shown) being adapted to surround the end region of the coupling 38 to clamp the same to the exhaust discharge pipe.

In the arrangement illustrated in FIGURE 1, the fittings or couplings 30 and 38 function as portions of inlet gas passage means and outlet gas passage means for conveying exhaust gases into and out of the interior of the muffler.

Disposed within the interior of the muffler are longitudinally spaced transversely extending partitions, walls or headers 42, 44 and 46. In the embodiment illustrated the headers 42, 44 and 46 are provided with aligned open-

ings to accommodate an inlet gas passage means or tube 48, the inlet end being telescoped into the coupling 30. The tube 48 is formed of a sheet of metal with the edge regions interlocked as shown at 49 in FIGURE 2. The wall or partition 46 is spaced from the end closure or head 22 providing a chamber 50 accommodating transverse flow of exhaust gases and providing a low frequency resonator or chamber for attenuating or absorbing low frequency sound waves. The inlet gas passage means 48 extends into the chamber 50.

The partitions or headers 42, 44 and 46 are provided with aligned openings to accommodate a second gas passage means or tube 54. The end closure 20 and the partition 42 define a low frequency resonator or chamber 56, the partitions 42 and 44 defining a second low frequency resonator 58 which is adjacent the resonator 56. The partitions 44 and 46 define a chamber 60. One end of the second gas passage means or tube 54 opens into the transverse gas passage chamber 50, the other end opening into and extending about midway in the low frequency resonator 56.

The transversely extending partitions 44 and 46 are formed with openings to accommodate a gas passage means or tube 62 one end of which extends a substantial distance into the resonator or chamber 58, the other end being telescoped into the coupling 38 providing a gas discharge means from the muffler. The header or partition 42 defining a wall of each of the low frequency resonators 56 and 58 is provided with an opening accommodating a frequency attenuating range modifying medium or tuning tube 64, portions of which extend substantial distances into the resonators 56 and 58 as shown in FIGURE 1. Each of the tubes 54 and 62 is fashioned of a sheet of metal with the edges overlapping as shown at 63 in FIGURE 2 and secured together as by welding.

The length and diameter of the tuning tube controls the frequency range of attenuation of the resonators 56 and 58 to modify within limits the resonant frequencies of these chambers. Means is disposed between the partitions 44 and 46 and cooperating with the gas passage means extending through the region between these partitions providing high frequency sound attenuating chambers. Extending lengthwise of the muffler between opposed wall portions of the inner layer 12 and adjacent the tube or gas passage means 54 is a baffle or partition 66 provided with flange portions 68 welded to the inner layer 12 as shown in FIGURE 2 and having its ends joined with the partitions 44 and 46.

Through the use of the lengthwise partition 66, the region of the gas passage tube 54 between the headers 44 and 46 is isolated from adjacent overlapping regions of the tubes 48 and 62. The walls of the gas passage tubes between the headers 44 and 46 are provided with comparatively large numbers of small openings 70, 72 and 74 which form acoustic couplings with the regions surrounding and adjacent the respective tubes. Thus the partition 66 forms with a portion of the inner shell 12 a high frequency sound attenuating chamber 76 for attenuating high frequency sound waves.

A partition 78 similar to partition 66 extends lengthwise of the muffler between opposed wall portions of the inner layer 12 as shown in FIGURE 2 and is provided with flanges 80 welded to the inner layer and having its ends joined with the partitions 44 and 46. The partition 78, with the adjacent wall portions of the inner shell or layer 12 provide a high frequency sound attenuating chamber 82 adjacent the perforated region of the gas passage means 62 as shown in FIGURE 2.

The region between the partitions 66 and 78 forms a high frequency sound attenuating chamber 84 which is isolated from the high frequency attenuating chambers 76 and 82. It should be noted that the small openings in the walls of the gas passage tubes between the headers 44 and 46 form acoustic couplings with the adjacent regions formed by partitions 66 and 78 and also provide

for the circulation of exhaust gases through the respective high frequency sound attenuating chambers.

In this manner the exhaust gases flow into the respective high frequency sound attenuating chambers and into the gas passage means passing through the chambers so that the exhaust gases are not trapped or held within the high frequency attenuating chambers. Through this arrangement the exhaust gases circulate through the high frequency sound attenuating chambers with little variation in the temperatures of the metal walls defining the chambers.

An important feature of the present invention is the provision of the dual low frequency resonators 56 and 58 arranged in adjacent relation and connected by a tuning tube 64. The provision of the tuning tube 64 facilitates the modification of the frequency attenuating range of the low frequency resonators to secure most effective sound attenuation of low frequency sound waves in a particular exhaust gas stream.

The length and the diameter of the tuning tube 64 modifies the frequency range of attenuation of the resonators 56 and 58. By shortening the tuning tube 64, the resonators 56 and 58 attenuate or absorb higher frequency sound waves and lengthening the tube lowers the range of frequencies attenuated or absorbed in these chambers. By using a smaller diameter tuning tube 64, the resonators attenuate sounds of lower frequencies and, conversely, a tuning tube of larger diameter, higher sound frequencies are attenuated, absorbed or damped by the resonators 56 and 58. The tuning tube 64 however should be of sufficient diameter to avoid increasing back pressure in the exhaust gas stream moving through the muffler.

In the operation of the muffler shown in FIGURES 1 and 2, the exhaust gases or the gases of a stream flow into the muffler through the gas passage means 48 into the transverse gas passage or chamber 50, thence in a reverse direction through the gas passage tube 54 into the resonator 56, through the tuning tube 64, resonator 58 and the outlet tube or gas passage means 62 whereby the gases are conveyed away from the muffler. It should be noted that the wall region of the tube 48 extending through the resonator chambers 56 and 58 is unperforated and the region of the intermediate gas passage means or tube 54 adjacent the resonator chamber 58 is unperforated.

In this manner the exhaust gases are caused to flow through all interior regions of the muffler defined by the inner layer or shell 12 and the end heads 20 and 22 so that there is a substantially uniform temperature of all components of the muffler under the influence of the heat from the exhaust gases.

Through this arrangement there are no pockets or "dead" chambers, that is, chambers in which exhaust gases do not circulate, so that there are no regions of extreme temperature differentials within the muffler.

The use of the tuning tube 64 facilitates the adjustment of effective attenuation of desired ranges of low frequency sound waves in the low frequency resonators 56 and 58. By reducing the likelihood of severe temperature differentials throughout various regions of the muffler construction, the tendency for the formation of condensation in the muffler is greatly reduced, minimizing the liability of corrosion and oxidation and hence providing for an increased life of the muffler construction.

FIGURE 3 is a fragmentary sectional view illustrating a modified form of means surrounding a gas passage tube or gas passage means providing a high frequency sound wave attenuating chamber. In this form of construction, the gas passage tube 62' is surrounded by a cylindrical shell or intermediate tube 88, in lieu of the partition 78 shown in FIGURES 1 and 2, which fits the curvature of the inner shell at the longer dimension of the ellipsoidal configuration. The tube 88 is formed of a sheet of metal with the edges overlapping as indicated at 89 and secured together as by welding. The housing construction is of

the same character as illustrated in FIGURE 1, the inner shell 12' being contiguous with the intermediate shell throughout approximately one half of the peripheral span of the intermediate tube. The partition or intermediate shell or tube 88 is welded or otherwise secured to the transverse headers so as to maintain the intermediate tube 88 in proper position in the muffler. It is to be understood that a tube of the character shown at 88 may be employed with the tube 54 shown in the construction of FIGURE 2, providing a high frequency sound wave attenuating chamber.

FIGURE 4 illustrates a modified form of the invention. This form of muffler construction comprises a dual wall shell, casing or housing 100 provided with end heads or closures 102 and 104 which are joined to the housing in the manner shown and described in connection with the form of the invention illustrated in FIGURES 1 and 2. The end head 102 is provided with an offcenter opening accommodating an inlet gas passage means or tube 106. The end head 104 is provided with a central opening accommodating a gas passage means or outlet tube 108.

Disposed within the housing 100 are transversely extending walls or partitions 110, 111 and 112 which are longitudinally spaced as illustrated. The gas passage inlet means or tube 106 extends through openings in all three of the partitions and opens into a gas transfer chamber 114 formed by the partition 112 and the end head 104. The region between the end head 102 and the partition 110 provides a low frequency sound attenuating resonator or chamber 116, and the partitions 110 and 111 define a second low frequency sound attenuating resonator or chamber 118, the low frequency resonators being arranged in adjacent relation.

A third gas passage means or tube 120 extends through openings in the three partitions 110, 111, 112, one end of the gas passage means 120 opening into the gas transfer passage or chamber 114, the other end opening into the low frequency resonator 116.

It should be noted that the gas outlet passage means 108 extends a substantial distance into the low frequency resonator 118. The partition 110 disposed between the low frequency resonators is provided with an opening to receive a gas passage tube 122, the latter extending substantial distances into the resonators 116 and 118.

The extremity of the tube 122 in the resonator 118 is spaced a substantial distance from the inner end of the gas passage outlet tube 108. The tube 122 provides a tuning means between the low frequency resonators 116 and 118, the length and size of which modifies the range of low frequency sound waves attenuated in the low frequency resonators. The wall portions of the gas passage tubes 106, 108 and 120 in overlapping relation between the partitions or transversely extending walls 111 and 112 are provided with a comparatively large number of small openings 123.

The perforated region of the tube 108 is isolated from the perforated regions of the gas passage tubes 106 and 120 by lengthwise extending partitions or separators 124 and 126 which may be of the character of the lengthwise partitions 66 and 78 in the form of the invention of FIGURES 1 and 2. It is to be understood that the isolation of the perforated region of the tube 108 may be attained through the use of intermediate cylindrical shells or tubes surrounding the perforated portions of tubes 106 and 120 in the manner illustrated in FIGURE 3.

Through the isolation of the perforated regions of each of the three tubes disposed between the partitions 111 and 112, high frequency sound attenuating chambers 127, 128 and 130 are provided at the perforated regions of the tubes. The openings in the tube walls provide acoustic couplings with the high frequency sound attenuating chambers surrounding the perforated portions of the tubes and means to facilitate the circulation of gases through the chambers 127, 128 and 130.

The portion of the gas passage tube 110 between the

end head 102 and the partition 111 and the portion of the gas passage tube 120 between the transverse partition 110 and 111 are unperforated.

In the operation of the muffler or silencer construction shown in FIGURE 4, the gas stream, such as an exhaust gas stream from an internal combustion engine, enters the inlet gas passage tube 106, the gases flowing into the transverse gas passage or chamber 114, some of the gases of the stream flowing through the perforations in the tube 106 and circulating through the high frequency attenuating chamber 128.

The gases flow transversely through the gas transfer passage 114, thence in a reverse direction through the gas passage means or tube 120 into the low frequency resonators 116, some of the gases entering the perforations or openings in the tube 120 and circulating through the high frequency sound attenuating chamber 130. The gases in the low frequency resonator 116 flow in a right-hand direction through the tuning tube 122, circulating through the low frequency resonator 118 and are discharged from the muffler through the outlet gas passage tube 108.

Some of the gases circulate through the high frequency chamber 127 surrounding a portion of the outlet tube 108. Thus it will be seen that gases moving through the muffler flow into and circulate through all of the chambers and passages so that a substantially uniform temperature obtains throughout all the interior regions of the muffler construction. The tuning tube 122 may be modified in size and length to influence the range of low frequency sound waves attenuated in the low frequency resonators 116 and 118.

FIGURE 5 illustrates another form of muffler construction of the invention. In this form the muffler preferably includes a double wall shell or casing 140 provided with end heads 142 and 143. The construction includes a gas passage means 144 extending through the end head 142 forming the gas inlet, a second gas passage means 146 extending through an opening in the end head 143 providing a gas discharge means for the muffler. In this form of construction, the inlet tube is offset from the central axis of the muffler and the outlet tube 146 is substantially on the central axis of the muffler.

Disposed within the shell 140 are transversely extending partitions or walls 145, 147 and 148 spaced longitudinally as illustrated. The inlet tube 144 extends through aligned openings in the three partitions and the outlet tube 146 extends parallel with the tube 144 through aligned openings in the several partitions. A third gas passage tube 150 extends through openings provided in the partitions 145 and 147. The partition 145 with the end head 142 defines a transverse gas transfer passage 152.

The partition 148 with the end head 143 defines a low frequency resonator or chamber 154 and the partitions 147 and 148 define a second low frequency resonator 156, the low frequency resonators being arranged in adjacent relation. The gas passage means or tubes 144, 146 and 150 are in overlapping relation and the walls of the overlapping portions of these tubes disposed between the partitions 145 and 147 are provided with a comparatively large number of small openings 149 forming acoustic couplings with the adjacent regions.

Disposed between the overlapping portions of the tubes and extending lengthwise between the transverse partitions 145 and 147 are lengthwise disposed partitions, separators or baffles 158 and 160 which may be of the character of the separators or baffles 66 and 78 in the construction illustrated in FIGURES 1 and 2. These lengthwise partitions isolate the overlapping perforated portions of each of the tubes 144, 146 and 150 between the partitions 145 and 147 and provide high frequency sound attenuating chambers, one chamber being adjacent to each of the perforated overlapping regions of the tubes.

The wall portion of the outlet tube 146 disposed between the partitions 147 and 148 is provided with a large

number of small openings 157 and this portion of the tube is surrounded by an intermediate cylindrical shell or tubular member 164. The annular space between the adjacent portion of the tube 146 and the intermediate shell 164 provides an additional high frequency sound attenuating chamber 165.

Extending through an opening in the partition 148 is a tuning tube 166 which projects a substantial distance into each of the resonators 154 and 156 as illustrated and provides a means for modifying the range of low frequency sound waves attenuated in the resonators 154 and 156.

In the operation of this form of construction the gases enter the inlet gas passage means 144 and flow into the low frequency resonator 154, some of the gases circulating through the high frequency sound attenuating chamber surrounding the perforated portion of the tube 144. The gases flow from the resonator 154 through the tuning tube 166 into and circulate in the second low frequency resonator 156 thence through the gas passage tube 150 into the gas transfer passage 152 and into the outlet tube 146 which conveys the exhaust gas out of the muffler.

The gases circulate through the high frequency sound attenuating chambers surrounding the perforated regions of the tubes 144, 146 and 150 so that the exhaust gases circulate throughout the entire interior regions of the muffler and thereby establish substantially uniform temperature throughout the muffler. Through the establishment of a more uniform temperature, the liability of cold regions existing in the muffler, which foster the formation of condensation, are avoided thus prolonging the life of the muffler construction.

It should be noted in this form that the first low frequency resonator 154 is adjacent the end head 143 at the outlet region of the muffler and the second low frequency resonator 156 is adjacent the first low frequency resonator.

In the arrangement shown in FIGURE 5, an increased zone of high frequency sound attenuation is provided through the added chamber defined by the intermediate tube or shell 164 surrounding an additional perforated portion of the tube 146 between the partitions 147 and 148.

FIGURE 6 is illustrative of another form of muffler construction of the invention. The muffler construction of FIGURE 6 preferably includes a double wall shell or casing 170 provided with end heads 172 and 174. The construction includes transversely extending longitudinally spaced walls, partitions or headers 176, 177 and 178. An inlet gas passage means or tube 180 extends through openings in the partitions and opens into a low frequency resonator chamber 182 defined by the end head 174 and partition 178.

A gas passage means 184 forming an outlet for the gases extends through the end head 174 and through aligned openings in the partitions. The end of tube 184 opens into a gas transfer passage 186 defined by the end head 172 and the partition 176. A second low frequency resonator 188 is defined by the partitions 177 and 178. A third gas passage means or tube 190 extends through openings in the partitions 176 and 177, one end of tube 190 opening into the gas transfer passage 186, the other end thereof opening into and extending a substantial distance in the low frequency resonator 188.

A tuning tube 192 extends through an opening in the partition 178, the tube extending substantially into both resonators 182 and 188. The length of the tube 192 or its size or both may be varied to modify the range of low frequency sound waves attenuated or absorbed in the resonators 182 and 188. The tubes 180, 190 and 184 overlap in the region between the partitions 176 and 177 and the walls of these tubes in this overlapping region are provided with a large number of comparatively small openings 194 forming acoustic couplings with the adjacent regions.

Disposed at each side of the centrally positioned tube 190 are lengthwise extending partitions or baffles 196 and 198 which are similar to the partitions 66 and 78

shown in FIGURE 2. The partitions 196 and 198 isolate each of the overlapping portions of the tubes between the partitions 176 and 177 forming three high frequency sound attenuating chambers 199, 200 and 201. The regions of the tubes 180 and 184 between the partitions 177 and 178 are perforated with a large number of small openings 202 forming acoustic couplings with the adjacent regions.

These perforated portions of the tubes 180 and 184 are each surrounded by an intermediate circular shell 204 which extends between the partitions 177 and 178 and form high frequency sound attenuating chambers 206 and 208. The intermediate shells 204 form side walls of the low frequency resonator 188. It should be noted that in this form of the invention there are five high frequency sound wave attenuating chambers and two low frequency resonators 182 and 188, the latter being in adjacent relation.

In the operation of this form of construction, the exhaust gases enter the inlet tube 180, the gases flowing into the low frequency resonator 182, some of the gases flowing through the openings or perforations 194 and 202, circulating through the adjacent high frequency attenuating chambers, such circulating gases re-entering the tube 180 and flowing into the resonator 182. The gases in the low frequency resonator 182 flow in a reverse direction through the tuning tube 192, circulating through the second low frequency resonator 188 thence through the gas passage tube 190 into the gas transfer passage 186.

The gases in the transfer passage 186 flow into the outlet tube 184 and away from the muffler. The gases moving through the perforated regions of the several tubes or gas passage means circulate through the high frequency attenuating chambers adjacent the perforated regions so that the gases moving through the muffler circulate throughout the entire regions interiorly of the muffler thus establishing a substantially uniform temperature throughout the interior of the muffler.

It should be noted that all of the gases must flow through the tube 180 into the resonator 182 thence into the gas transfer passage 186 and through the full length of the outlet tube 184. In this manner all of the gases traverse substantially full length of the muffler, moving in a substantially S-shaped path. It should be noted that in this form of construction five high frequency sound attenuating chambers are provided for attenuating high frequency sound waves.

FIGURE 7 illustrates still another form of the muffler construction of the invention. In this form the muffler preferably includes a double wall shell 220 provided with end heads 222 and 224. Disposed interiorly of the shell 220 are four transversely extending walls or partitions 226, 227, 228 and 229, which are spaced lengthwise of the shell or housing. An inlet gas passage means or tube 230 extends through an opening in the end head 222 and through an opening in the partition 226 and opens into a low frequency resonator 232.

A second gas passage tube or outlet tube 234 extends through an opening in the end head 224 and through openings in the partitions or walls 228 and 229, one end of the tube opening into a transverse gas passage or chamber 236. A third gas passage means or tube 238 extends through openings in partitions 226, 227, 228 and 229, one end of the tube opening into a second gas transfer passage 240 defined by the end head 224 and the partition 229, the other end of the tube 238 opening into a second low frequency resonator or chamber 242.

Another gas passage means or tube 244 extends through openings in the partitions 228 and 229, the respective ends of tube 244 opening into the gas transfer passages 236 and 240. A tuning tube 246 extends through an opening in the partition 226 and establishes communication between the two low frequency resonators 232 and 242, the tube 246 extending a substantial distance into each of the resonators. The length or size of the tuning

tube 246 may be changed in order to vary the range of frequency of sound waves absorbed in the low frequency resonators 232 and 242.

The portion of the tube 238 within the low frequency resonator 232 is provided with a comparatively large number of small openings 248. Extending lengthwise between the partitions 226 and 227 is a longitudinal partition or separator 250 which forms a wall of the low frequency resonator 232 and isolates the perforated region of tube 238 between partitions 226 and 227, forming a high frequency sound wave attenuating chamber 252.

The regions of the tubes 234, 238 and 244 in overlapping relation between the partitions 228 and 229 are provided with small openings or perforations 256. Extending lengthwise between the partitions 228 and 229 and at each side of the tube 234 are lengthwise extending separators, baffles or partitions 260 which form high frequency sound wave attenuators 262, 264 and 266.

Thus in this form of construction there are four high frequency sound wave attenuating chambers.

The operation of this form of construction is as follows: The exhaust gases enter the inlet tube or gas passage means 230 and flow into the resonator chamber 232. The gases in the resonator chamber 232 flow in a reverse direction through the tuning tube 246 into the second resonator chamber 242. The gases in the resonator 242 flow through the gas passage tube 238 into the gas transfer chamber 240, thence in a reverse direction through the tube 244 into the second gas transfer passage 236. The gases in the transfer passage 236 flow through the exhaust outlet tube 234 and away from the muffler.

Some of the gases flowing through the perforated regions of the gas passage tubes enter the high frequency sound attenuator chambers adjacent the tubes so that there is a circulation of gases throughout the entire interior regions of the muffler establishing a substantially uniform temperature throughout the entire interior regions of the muffler.

By shortening the tuning tube in the forms of the invention the range of frequencies attenuated is increased. By making the diameter of the tuning tube smaller or lengthening the tube the range of frequencies of sound waves attenuated is lowered.

It is apparent that, within the scope of the invention, modifications and different arrangements may be made other than as herein disclosed, and the present disclosure is illustrative merely, the invention comprehending all variations thereof.

I claim:

1. A muffler for use with a moving gas stream including, in combination, an elongated tubular shell provided with end walls, a plurality of longitudinally spaced transverse walls intermediate the end walls in said shell and extending completely across the inside of the shell, certain of said walls defining dual low frequency resonators and transverse gas transfer means, said dual resonators being arranged in adjacent relation, said gas transfer means being spaced from the low frequency resonators, a plurality of gas passage means extending lengthwise in said shell, one of said gas passage means providing a gas inlet and another of said gas passage means providing a gas outlet for the shell, a third gas passage means connecting said gas transfer means with one of the low frequency resonators, and a tuning tube disposed in an opening in the wall intermediate the dual low frequency resonators and extending a substantial distance into each of the resonators, said gas transfer means and said low frequency resonators and third gas passage means being arranged whereby gases moving through the muffler flow through both low frequency resonators in sequence.
2. A sound attenuating means for use with a gas stream, in combination, an elongated tubular housing, end walls secured to the housing, said end walls being provided with gas inlet and outlet openings, a gas passage tube in said

housing in registration with the inlet opening, a second gas passage tube in said housing in registration with the outlet opening, a plurality of transversely extending, longitudinally spaced intermediate walls in said housing, one of said walls being disposed between another of said walls and an end wall and defining two adjacent low frequency resonators, the opposite end wall and the adjacent intermediate wall forming a transverse gas passage means, an open ended pipe extending through the wall between the resonators and projecting a substantial distance into each resonator, and a third gas passage tube in said housing for directing the gases from the inlet tube for traverse through both low frequency resonators in sequence.

3. A sound attenuating means for use with a gas stream, in combination, an elongated tubular shell, end heads secured to the shell, an inlet gas passage tube extending through one of said heads into the shell, an outlet gas passage tube in said shell extending through the other end head, at least two transversely disposed longitudinally spaced partitions in said shell defining with one of said end heads a pair of low frequency resonator chambers, a tuning tube extending through the partition between the chambers and projecting a substantial distance into each chamber, transverse gas passage means in said shell formed by the other end head and an adjacent partition, and a third gas passage tube in communication with the transverse gas passage means and one of the low frequency resonators arranged to direct all of the gases from the inlet gas passage means into the resonator chambers for discharge through the outlet gas passage means.

4. A sound attenuating means for use with a gas stream, in combination, a tubular shell, end heads secured to the shell, a gas inlet tube in said shell extending through an opening in one of said heads, a gas outlet tube in said shell extending through an opening in the other of the heads, a third tube in said shell arranged in

transverse overlapping relation with said inlet and outlet tubes, a plurality of transversely disposed partitions in said shells extending completely across the inside of the shell, two of said partitions and an end head defining 5 two low frequency resonator chambers in adjacent relation, a tuning tube disposed in an opening in the partition intermediate the low frequency resonator chambers, the walls of the overlapping regions of said tubes between two of said partitions being provided with a comparatively large number of perforations, lengthwise extending baffle means separating the perforated overlapping regions of the tubes one from another forming high frequency sound attenuating chambers, a transverse gas transfer passage formed by the opposite end head and an adjacent 10 partition establishing communication with two of said tubes providing for flow of gases through said two tubes in opposite directions and through the low frequency resonator chambers in sequence, said perforations in the overlapping portions of said tubes forming acoustic 15 couplings with the high frequency sound attenuating chambers.
